DISPLAY STAND

Nathan H. Poor, Stratford, Conn., assignor to The American Fabrics Company, Bridgeport, Conn., a corporation of Connecticut

Application December 24, 1952, Serial No. 22,861

Term of patent 3½ years

(Cl. D80—9)

To all whom it may concern:

Be it known that I, Nathan H. Poor, a citizen of the United States, residing at Stratford, county of Fairfield, State of Connecticut, have invented a new, original, and ornamental Design for a Display Stand, of which the following is a specification, reference being had to the accompanying drawing, forming a part hereof.

Fig. 1 is a front elevational view of a display stand, showing my new design, with a portion broken away for better illustration;

Fig. 2 is a side view thereof, and

Fig. 3 is a top plan view.

The broken lines shown in Fig. 1 are for illustrative purposes only.

I claim:

The ornamental design for a display stand, substantially as shown and described.

NATHAN H. POOR.
